TYPEWRITER

Carlos Wittenmyer, Mount Clemens, Mich.

Application February 19, 1937, Serial No. 126,626

6 Claims. (Cl. 197—178)

My invention relates to typewriters and an object of my improvements is to facilitate the entry of figures in their proper decimal relation.

I have shown my invention in the kind of machine which employs a continuously rotating actuating cylinder and for convenience it is assumed that figures of the order of 10,000, 1,000, 100, 10, 1, and .1 with their conventional punctuating marks are to be entered in their respective positions.

In the accompanying drawings:

Figure 1 is a front elevation of a typewriter embodying my invention, the casing being partly broken away.

Figure 2 is an elevation to an enlarged scale showing the typewriter casing in section and the positioning apparatus therein, looking from the front of the machine.

Figure 3 is a diagrammatic elevation looking from the position indicated by the line 3—3 3—3, Figure 2, and in the direction indicated by the arrows at the ends of said line. The tabulating and spacing levers and connecting mechanism are however shown, which are in fact at the left of the line 3—3 3—3 as shown in Figure 2.

Figure 4 is a detail elevation and section on the line 4—4, Figure 2, looking in the direction of the arrows.

Figure 5 is a view similar to Figure 2, but showing the parts in a different position.

Figure 6 is a view similar to Figure 5, but only showing the lower portion of said figure, the parts being in still another position.

Figure 7 is a view similar to Figure 6, the parts being in a different position.

Referring in the first place to Figure 1, A, is the typewriter casing; P, the platen carriage; and K, the bank of keys; S, is the spacer bar; B, the back spacer; and T, the tubular key.

Above the bank of keys, K, is shown a row of decimal tabular keys designated respectively by the order of numerals, or incidental punctuations, to which they relates as 10,000, 1,000, ., 100, 10, 1, ., 1. The actuation of any one of these keys brings the platen carriage to the position for printing figures of the order indicated, or the incidental punctuating mark, as hereinafter described.

2 is a bail bar pivoted at its ends to the sides of the frame A and serving to guide the movement of the universal bar 2a which is pivoted at its ends upon, and extends parallel to and above, said bail bar. T is the tabular key; T2 the tabular key bar; and T2a a connecting link between the universal bar 2a and the tabular key bar T2.

The lower end of the decimal tabular key 100 engages the universal bar 2a (Figure 2) and when said key is depressed the universal bar is pressed down thereby, and the bar T2 is drawn down by the connecting rod T2a and the platen carriage P

is brought to the position for printing in the hundreds column.

3 and 4 are cam wheels having alternate elevations, or salients, and depressions in their peripheries. One of said elevations 3a or 4a in each wheel is higher than the others and has a more extended face or outer edge. 3b and 4b are pinions coaxial and integral with the cam wheels 3 and 4. 3c and 4c are inertia dogs engaging the cams 3 and 4 to prevent too rapid motion or an overthrow.

5 is a rod pivoted at one end on the axle of the cam wheel 4 extending across the typewriter casing and at its other end provided with an arcuate toothed rack 5a, the teeth of which engage the teeth of the pinion 3b.

6 is a rod entirely similar in construction and location to the rod 5, but pivoted at the opposite side of the casing A upon the axle of the cam wheel 3, its arcuate outer end engaging the pinion 4b.

7, 7 are tension springs tending to raise the levers 5 and 6 to the upper ends of their travel.

a, a, a indicate the stems of the tabular keys to the left of the 100 key and a1, a1, a1, the stems at the right of said key. Each of these keys a and a1 has a branch 8 (Figure 3) extending over the universal bar 2a. Each of the keys a has a second branch 9, the lower end of which rests upon the bar 5, and each of the keys a1 has a similar branch 10 resting upon the bar 6.

11 and 12 are levers of like construction pivoted to the casing A at opposite sides thereof and having dolly rolls 11a and 12a on their inner ends adapted to engage respectively the peripheries of the cam wheels 3 and 4. 13—13 are springs tending to force the inner ends of the levers 11 and 12 down and therefore the dolly rolls 11a and 12a against the peripheries of their respective cam wheels. 14—14 are spring actuated catches which engage and hold the inner ends of the levers 11 and 12 at the upper ends of their travel.

15 is a link connecting the inner end of the lever 11 with the back spacer key bar B2 and 16 is a similar link connecting the inner end of the bar 12 with the spacer bar S. 17—17 are bars connecting the universal bar 2a with the tripping mechanism of the catches 14—14.

The operation of the above described apparatus is as follows:

When one of the decimal tabular keys, except the hundreds key, is depressed it first engages a lever 5 or 6 and turns a cam wheel 3 or 4 to a position that places that portion of its periphery which corresponds with the ordinal of the space of the character the key represents to the right or left of the hundreds space, in position to be engaged by the dolly rolls 11a or 12a of the lever 11 or 12. On still further depressing said key, the lower end of its branch engages the universal bar 60

2a, pressing it down, disengaging the catch 14 and allowing the inner end of the lever 11 or 12 to descend engaging the dolly rolls 11a or 12a on the periphery of the wheel 3 or 4. When the key is released the lever 5 or 6 rises, turning a cam wheel 3 or 4 back to its previous position. As the cam wheel turns the dolly roll rides over the convexities and into the cavities of the cam wheel, thus causing the lever 11 or 12 to oscillate, which works the spacer bar S, or back spacer key bar B2, the required number of times to bring the platen carriage into position to print characters of the order indicated by the designation of the key.

When the cam wheel has returned to its original position, the dolly roll rides upon the outer edge of the salient portion 3a or 4a, and the catch 14 again automatically engages the lever 11 or 12. The other salient portions of the cam wheels 11 and 12 are not as high as the portion 3a or 4a, so that the levers 11 or 12 passing over them are not raised high enough to cause the engagement of the catch.

More specifically the action is as follows:

The parts being in the position shown in Figure 2, if one wishes to print a figure of the order of 10,000, he presses the 10,000 key down. Its branch 9 first presses down upon the lever 5 turning the cam wheel 3, by means of the rack 5a and pinion 3b to the position shown in Figure 5. On further downward motion it turns the cam wheel a little further, the stem of the key engages the universal bar 2a depressing the same and loosening the catch 14 permitting the lever 11 to fall upon the top of the next convexity as shown in Figure 6. The depression of the universal bar 2a also actuates the tabular key bar T2 through the connecting rod T2a, bringing the platen carriage to the hundreds position, as indicated in Figure 1 in full lines. On releasing the key, the parts are carried back to their first position by the various springs. The dolly roll 11a will fall into the three cavities and pass over the intermediate salient portions thus actuating the back spacer bar B2 three times and bringing the platen carriage to the required position as shown in broken lines in Figure 1.

In placing the platen carriage in any position to the left of the hundreds key an entirely analogous operation would take place, except that the lever 6 and the mechanism at the left of the casing would, by means of the connecting rod 16, oscillate the spacer bar S, permitting the platen carriage to move the required number of spaces to the left of the 100 position as indicated in full lines in Figure 1.

The apparatus herein described may be connected to the regular typing keys and the space bar in the same manner as shown connected to the tabulating keys. One adaptation of this would be to produce written matter in the negative to produce a master from which duplicates are later produced. In this case, a type key would cause the carriage to backspace two times and the space bar would cause the carriage to backspace two times, on the upward travel of said key bars, as by means of the key 1,000 above described.

This method of construction will eliminate costly changes in the construction of an escape-
70 ment mechanism designed to move the carriage from left to right instead of the conventional con-

struction which allows the carriage to move from right to left when typebars or spacer key is operated.

Of course the type will be reversed laterally and the line will begin at the right of the paper and end at the left. The carriage will be placed at the left and will be spaced toward the right by the back-spacing key.

What I claim is:

1. In a typewriter having a means for locating the platen carriage for a tabular purpose, and means adapted to space said carriage in one direction and means adapted to space said carriage in the other direction, a key adapted to actuate said tabular means on one stroke and one of said spacing means on the other stroke and a key adapted to actuate said tabular means on one stroke and the other of said spacing means on its other stroke.

2. In a typewriter having a tabular carriage-positioning means and a carriage-spacing means, a member having a cam surface means for actuating said member adapted to actuate said tabular means on one stroke, means intermediate said member and said spacing means adapted to permit the passage of said cam surface on said stroke and to be actuated by said cam surface on its return stroke.

3. In a typewriter having a tabular carriage-positioning means and a carriage-spacing means, a member having a cam surface means for actuating said member adapted to actuate said tabular means on one stroke, means intermediate said member and said spacing means adapted to permit the passage of said cam surface on said stroke and to be actuated by said cam surface on its return stroke a predetermined number of times.

4. In an apparatus of the kind described, a movable member having a plurality of cam surfaces one of which rises to a higher point than any other, a part adapted to be reciprocated by said cam surfaces, a catch adapted to engage said part when engaged by said point at the initial position of said member and means whereby said member is actuated and then said catch is disengaged and means for automatically returning said member to its initial position.

5. In a typewriter having a platen-carriage-spacing means, a movable member having a plurality of cam surfaces one of which rises above any other, a part adapted to be reciprocated by said cam surfaces, a catch adapted to engage said part when engaged by said point at the initial position of said member and means whereby said member is actuated and then said catch is disengaged, means for automatically returning said member to its initial position, said part being connected to said spacing means.

6. In a typewriter having a tabular positioning means, and a spacing means, a row of decimal tabulating keys, a lever pivoted at one side of the typewriter casing and extending across said casing beneath said keys, a cam wheel at the movable end of said lever, said lever being adapted to turn said cam wheel, a part connected to said spacing means adapted to be actuated by said cam wheel, a bar extending beneath said decimal keys adapted to be moved to actuate said tabular positioning means, said keys being adapted to actuate said lever and then to actuate said bar.

CARLOS WITTENMYER.
